G. B. POINDEXTER,
BURGLAR ALARM FOR MOTOR VEHICLES,
APPLICATION FILED FEB. 20, 1919.

1,318,299.

Patented Oct. 7, 1919.

Inventor
George B. Poindexter
By his Attorney
Frank Warren

UNITED STATES PATENT OFFICE.

GEORGE BENJAMIN POINDEXTER, OF SEATTLE, WASHINGTON.

BURGLAR-ALARM FOR MOTOR-VEHICLES.

1,318,299.

Specification of Letters Patent.

Patented Oct. 7, 1919.

Application filed February 20, 1919. Serial No. 278,297.

To all whom it may concern:

Be it known that I, GEORGE BENJAMIN POINDEXTER, a citizen of the United States, residing at Seattle, in the county of King and 5 State of Washington, have invented a certain new and useful Improvement in Burglar-Alarms for Motor-Vehicles, of which the following is a specification.

My invention relates to improvements in 10 burglar alarms for automobiles and the object of my invention is to provide a lock-controlled alarm of relatively cheap and simple construction that may be easily installed on an automobile in connection with 15 the ignition system so that when the automobile is left standing in a public place the alarm may be set in such a position that it will be automatically sounded if current is caused to flow through the conductors that 20 lead to the spark plugs in an attempt to start the automobile.

I accomplish this object by devices illustrated in the accompanying drawings, wherein—

25 Figure 1 is a view partly in section and partly in elevation of an alarm constructed in accordance with my invention; and

Fig. 2 is a plan view of the same with the cover removed.

30 Referring to the drawings throughout which like reference numerals indicate like parts, the numeral 5 designates a rectangular metallic box, the walls of which are provided with relatively small perforations that 35 permit sound to escape from the box 5 and such box being of strong and solid construction so that it will be difficult to gain access thereto.

The box 5 is secured to the car and arranged 40 so that the spark control rod 7 that extends from the steering wheel downwardly along or through the steering post may pass therethrough and the spark control rod 7 is provided within the box 5 with a fixedly mounted arm 8 preferably of fiber that projects at right angles therefrom and turns with the rod when the latter is oscillated to control the spark.

Pivoted to the bottom of the box 5 by a 50 hinge 10 is a plate preferably of fiber or other suitable insulating material that projects upwardly at one side of the spark control rod 7 and has two U-shaped contact carriers 12 and 13 secured thereto in insulated relation with respect to each other. 55 The contact carriers are preferably formed

of spring metal and are provided with contact members 14 and 15 respectively that are adapted to be bridged by a contact bar or switch blade 16 that is carried by the arm 8, the sides of the contact members 14 and 15 that are first engaged by the arm 8 being inclined or beveled so that the contact bar 16 will ride over them more easily when the arm is turned from an upright position 65 into the position shown in Figs. 1 and 2.

17 is a plunger having an inclined or beveled outer end that is adapted to project within a hole 18 in the contact bar 16 the plunger 17 being guided and supported for 70 endwise movement within suitable holes in the spring 12 and fiber plate 11 and being urged outwardly by a relatively light compression spring 20 that is arranged to press 75 against a collar 21 on the plunger.

Secured to the rear side of the fiber plate 11 is a two part socket 22 that fits over a ball 23 on the end of a shank 24. The outer end of the shank 24 is externally threaded and is adapted to screw within the internally 80 threaded inner end of a lock socket 25. The lock socket 25 projects outwardly through and is somewhat loosely secured to the side of the box 5 and the end of such socket is provided with an inserted rotatable member 85 26 having a peculiarly shaped key hole wherein a key 27 may be inserted.

The threaded end of the shank 24 has a longitudinally extending keyway 28 that is suitably ridged and channelled for the reception of the key 27 and the end of such shank 90 is provided with one removable section 30 that is secured by screws 31 to the main part of the shank and that may be removed and replaced by a section that is ridged and 95 channelled in a different manner and which will require a different key to operate.

The fiber plate may be tilted to the left from the position shown in Fig. 1 by inserting the key 27 and screwing the shank 24 100 into the socket 25 thereby moving the contacts 14 and 15 away from the arm 8 so that the arm 8 may oscillate freely without touching such contacts.

The spring 12 is connected by an electric 105 circuit wire 32 with a circuit wire 33 that leads from a source of supply of current, as from a storage battery and the spring 13 may be connected by an electric circuit wire 34 with one terminal of an electric 110 bell 36, the other terminal of the bell 36 being grounded so that when the circuit is

closed by bridging the terminals 14 and 15 current will flow through the bell and cause it to ring.

- In operation when the device is installed 5 as hereinbefore described with the fiber plate 11 in the position shown in Figs. 1 and 2 and the spark retarded, the contact arm 8 will be turned into a substantially upright position thereby opening the switch formed by the 10 contact members 14 and 15, but when the spark is advanced to start the engine the contact arm 8 will be turned downwardly into a substantially horizontal position thereby bridging the contact terminals 14 15 and 15 and causing the bell 36 to ring.

When the automobile is in use the driver will insert the key 27 into the lock and by turning the shank 24 will tilt the fiber plate 11 to the left as viewed in Fig. 1 until the 20 contact members 14 and 15 are withdrawn a sufficient distance to be clear of the path of movement of the contact bar 16 when the latter is moved by oscillation of the spark control rod 7 thus making it possible to 25 oscillate the rod 7 at will without closing the circuit to the bell 36.

When the automobile is to be left standing in a location where there is danger of 30 its being stolen the driver will insert the key 27 and by turning the shank 24 will move the fiber plate 11 into such a position that the contact members 14 and 15 are in the path of movement of the contact bar 16 and will be bridged by such bar when the 35 spark control rod 7 is rotated thereby closing the circuit and ringing the bell 36.

When the contact bar 16 is moved into the position shown in the drawings to close the 40 circuit the plunger 17 will enter the recess 18 and lock the bar in such position thus preventing the circuit from being again broken until the plate 11 is moved away from the arm 8 by turning the shank 24.

The lock socket 23 is secured in the side 45 of the casing 5 in such manner that it will not rotate but is free to move or tilt slightly to compensate for the tilting movement of the fiber plate 11.

While I have described this alarm mechanism as connected with the spark control 50 rod of an automobile it will be understood that the same will operate when connected with any shaft or similar member that oscillates.

Obviously changes in the precise form of 55 construction and arrangement of parts of my invention may be made without departing from the spirit thereof.

What I claim is:

- 60 1. Burglar alarm for motor vehicles comprising a casing, a shaft arranged to project into said casing, a plate hinged to one side of said casing, switch terminals carried on said plate in insulated relation with respect to each other, an arm secured to said

shaft, a switch bar on said arm arranged to bridge said terminals, means for moving said plate away from said arm to move said terminals out of the path of said switch bar, an electric bell, and an electric circuit connecting with said bell and arranged to be closed when said contact bar bridges said terminals. 70

2. Burglar alarm for motor vehicles comprising a casing, a shaft mounted for oscillation and arranged to project into said casing, a plate hinged to one side of said casing, switch terminals carried on said plate in insulated relation with respect to each other, an arm secured to said shaft, a switch bar on said arm arranged to bridge said terminals, means for locking said switch bar in engagement with said terminals, key operated means for moving said plate away from said arm to move said terminals out of the path of said switch bar, an electric bell and an electric circuit connecting with said bell and arranged to be closed to ring said bell when said contact bar bridges said terminals. 75

3. Burglar alarm for motor vehicles comprising a casing, a shaft arranged to project into said casing, a support hinged to the side of said casing, two terminals carried by said support in insulated relation with respect to each other, an arm secured to said shaft, a contact bar on said arm and arranged to make electrical contact between said terminals when said shaft is oscillated, a lock provided in one side of said casing, a shank 100 adapted to screw into said lock, a key arranged to fit said lock and turn said shank, a universal joint connecting said shank with said upright support whereby said support may be moved toward and away from said 105 contact bar by turning said shank, an electric bell, and an electrical circuit connected with said bell and arranged to be closed when said contact bar engages said terminals. 90

4. A burglar alarm for motor vehicles comprising a casing, a shaft adapted to project into said casing, a support hinged to one side of said casing, two U-shaped spring members secured to said support and insulated from each other, switch terminals on said spring members, an electric bell, an electric circuit connected with said bell through said switch terminals, an arm secured to said shaft, a switch bar on said arm and arranged to close the contact between said terminals, a lock member accessible from the exterior of said casing said lock member having an internally threaded socket, an externally threaded shank arranged to screw into said socket, a key adapted to be inserted in said lock member to turn said shank and a universal joint connecting one end of said shank with said upright support whereby said support may 110 115 120 125 130

be moved toward and away from said contact bar.

5. The combination with the spark control shaft of a motor vehicle, of a casing arranged to have said spark control shaft project therethrough, a plate hinged to one side of said casing, two U-shaped spring members secured to said plate and insulated from each other, switch terminals on said 10 spring members, a contact arm on said spark control shaft, a switch blade on said contact arm and arranged to connect said switch terminals when said shaft is oscillated said switch blade having a recess 15 therein, spring detent means arranged to enter said recess and lock said switch blade in engagement with said terminals, a lock member accessible from the exterior of said casing said lock member having an inter-

nally threaded socket, an externally threaded 20 shank arranged to screw into said lock member said shank being provided with a longitudinally extending keyway, a key adapted to be inserted into said lock and into the keyway in said shank to turn said shank, a 25 universal joint connecting one end of said shank with said hinged plate, an electric bell disposed within said casing, a circuit wire connecting one of said spring members with a source of electricity, and another circuit 30 wire connecting said other spring member with one terminal of said electric bell the other terminal of said bell being grounded.

In witness whereof, I hereunto subscribe my name this 11th day of February, A. D. 35 1919.

GEORGE BENJAMIN POINDEXTER.
